UNITED STATES PATENT OFFICE.

RUDOLF SENNER, OF PFORZHEIM, GERMANY.

AUTOMATIC MATCH-IGNITOR.

SPECIFICATION forming part of Letters Patent No. 484,253, dated October 11, 1892.

Application filed June 2, 1892. Serial No. 435,321. (No model.)

To all whom it may concern:

Be it known that I, RUDOLF SENNER, a subject of the Grand Duke of Baden, and a resident of Pforzheim, in the Grand Duchy of Baden, German Empire, have invented a certain new and useful Improved Automatic Match-Ignitor, of which the following is a full, clear, and exact description.

The automatic match-ignitor forming the object of the present invention consists, mainly, of a match-receptacle having a match-lifter vertically movable therein, and by means of which a match may be lifted up into the path of a spring-pressed match-projector. The latter is adapted to thrust the match forward, whereby the head is caused to come into contact with frictional surfaces, by means of which the said match is ignited as it is thrust out of the receptacle. Said projector, however, does not thrust the match right out, but allows the tail end of the same to remain clamped by the spring-pressed frictional igniting-surfaces.

In order to make this specification more easily intelligible, reference is had to the accompanying drawings, forming part of this specification, and in which similar letters denote similar parts throughout the several views.

Figure 1 is a front elevation showing the match in position after it has been projected and ignited. Fig. 2 is a plan of Fig. 1. Fig. 3 is a vertical section on line $\alpha\alpha$ in Fig. 1. Fig. 4 is a partial back elevation with the back plate of the receptacle removed. Fig. 5 is a detail view of the spring-pressed igniting-surfaces. Fig. 6 is a detail view showing a device for preventing a too rapid rise of the lifter.

The match-receptacle a is supported on its stand or foot-plate b between the side plates $a'a'$ and provided with an opening at the back, having a hinged door a^2 , through which the matches may be introduced. The receptacle has a sloping bottom a^3 , having at its lowest point a slot a^4 , through which the sliding match-lifter c projects. The said match-lifter has a groove at the top for the reception of a match, and is flanged outwardly at c' at the bottom. It is vertically movable on the guide-rods $d d$, passing through holes in flange c' and on which it is guided by the

arms c^3 , rigidly attached to the said flange c' , said arms being bent round rectangularly at the top and engaging the vertical rods $d d$ at 55 c^2 . The rods $d d$ may be provided with helical springs $d' d'$, on which the collars c^2 rest, said springs being compressed when the lifter c is depressed and being adapted when the latter is released to press it upward. The 60 match-projector k' is arranged at the top of the receptacle a and propelled forward by the arm h^2 of a bell-crank lever $h' h^2$, working in a slot in said projector, said lever being pivoted to the front wall of the receptacle at 65 h and having actuating-spring i , attached at its lower end to the horizontal arm h' and at 70 its upper end to a bracket l^3 , screwed to the side of the receptacle a . The bracket l^3 carries, further, the spring l , having an upwardly-projecting hooked arm $l' l^3$, forming the retaining-catch for the projector k' when the latter is drawn back previous to discharging the match.

The flange c' of the match-lifter c carries a 75 vertical arm e , rigidly attached thereto and having a pin e' at its upper end. The pin e' serves a double purpose: First, when the lifter c is drawn down (by hand) it engages on the arm h' of the bell-crank lever $h' h^2$, depressing 80 the same, stretching the spring i , and retracting the projector k' , and, second, when the lifter is raised either by the springs $d' d'$ or by hand (if for the sake of simplifying the apparatus these springs are omitted) the said 85 pin e' engages under the hook l^3 of the spring-catch $l l'$, thus raising the same and releasing the projector. The friction-surfaces z' are mounted on a spring z^2 at the discharge-hole z^3 for the match and serve to ignite the latter as 90 it is discharged, clamping its tail end, however, through their spring z^2 to prevent the match from falling out altogether. In case the springs $d' d'$ are employed, and in order to prevent a too-rapid rising of the lifter under the influence of the same after it has been depressed, it is advisable to employ some form of breaking or check device—such, for instance, as shown in Fig. 6. The lifter c is provided with a vertical rack f , having stationary guide-piece f' at its back and engaging with a pinion g' , fixed on a spindle g , supported in the sides $a'a'$ of the receptacle a , underneath the latter. Fixed to the spindle 100

g is a ratchet-wheel g^2 , and loosely mounted on the same a spur-wheel g^3 , carrying on its face a pawl g^4 to engage said ratchet-wheel. The spur-wheel g^3 gears with a pinion g^6 , 5 mounted on a spindle g^7 , carrying a weighted drum g^8 . On the downward movement of the lifter the drum will remain stationary as the pawl slips over the teeth of the ratchet-wheel; but on allowing the lifter to rise under pressure of the springs d' the said drum will be rotated, thus acting as a brake or check mechanism and preventing the lifter from rising too suddenly.

The device operates in the following manner: Matches, preferably wax vestas, are placed into the receptacle a with their heads toward that side of the same on which the igniting-surfaces z' are fixed. The flange c' is now pressed downward by hand until the 15 pin e' has sufficiently depressed the arm h' of the bell-crank lever $h' h^2$ to bring the projector k' under the catch $l l'$, Fig. 4. When this has been accomplished, the upper grooved 20 edge of the lifter will be at the bottom of the receptacle a , and on being released will rise, taking with it a match, as shown in Fig. 4. It now continues to rise under the action of the 25 springs $d' d'$ and checking mechanism until it has lifted the match into the line of discharge of the projector. At the same moment, however, the pin e' of arm e engages under the hook l^2 of the spring-catch $l l'$, raising the latter and releasing the projector, which flies forward under the action of the 30 spring i , thus discharging the match at z^8 , the same being ignited as its head passes the spring-pressed friction-surfaces z' , which also serve to clamp the tail end of the same fast, retaining it in the position shown in Fig. 1. 35 On this device, as previously indicated, the springs d' and check mechanism may be omitted, if it is desired to simplify the mechanism, for instance, in order to produce a cheaper article.

I claim as my invention—

1. An automatic match-ignitor composed of a match-receptacle with inclined bottom and a slot at the lower end thereof, a match-lifter movable vertically in said slot and having at the top a groove for receiving a match, a 45 match-projector guided horizontally in the line, into which the match is raised by the lifter when being at the top of its course, an elbow-lever in connection with and operating the projector, a spring acting on the lever to drive the projector against the tail end of the match when raised, a spring-catch arranged to retain the projector rearward of the match, a pin in rigid connection with the match-lifter and adapted on descending to operate 50 the said lever to retract the projector and on rising to disengage the catch from the projector, and frictional spring-pressed surfaces placed in a line with the path of the projector and adapted to ignite the match when it is 55 thrust along the same, substantially as described.

2. An automatic match-ignitor composed of a match-receptacle a , having inclined bottom a^3 and slot a^4 , a vertically-movable match-lifter c , having a groove at the top, a match-projector k' , having guide-rods k , a bell-crank lever $h' h^2$, pivoted at h and having spring i , a spring retaining-catch $l l'$, having hook l^2 , a rigid arm e on the match-lifter having pin e' , frictional spring-surfaces at the discharge-opening for the match, springs d' , in connection with the lifter, to raise the same, and suitable check mechanism to prevent the too sudden action of said springs, substantially 75 as described.

In testimony whereof I have hereunto set my hand in the presence of two subscribing witnesses.

RUDOLF SENNER.
